UNITED STATES PATENT OFFICE.

BLOOMFIELD H. HOWARD, OF WASHINGTON, DISTRICT OF COLUMBIA, AND ERNEST J. TURNER, OF PITTSBURGH, PENNSYLVANIA.

CASTING FOR FEEDERS FOR INGOT MOLDS.

Application filed February 9, 1924. Serial No. 691,739.

To all whom it may concern:

Be it known that BLOOMFIELD H. HOWARD and ERNEST J. TURNER, citizens of the United States, residing, respectively, at 5 Washington, District of Columbia, and Pittsburgh, in the county of Allegheny and State of Pennsylvania, have invented certain new and useful Improvements in Castings for Feeders for Ingot Molds, of which 10 the following is a specification.

Our invention relates to improvements in castings for feeders for ingot molds.

The object of our invention is to provide a casting for forming ingot mold feeders 15 made of plastic material by forcing it through a casting having a passage therethrough corresponding to the form of feeder.

Another object of our invention is to provide a casting in which the outer walls of the feeder are bellied inwardly and provided with integral ribs and having an inner wall of approximately the same contour whereby a perfect feeder is formed by forcing 25 the plastic material through said casting by a plunger such as shown in the drawings of this application.

A further object of our invention is to provide a specially shaped casting adapted 30 to form a correspondingly shaped feeder and having certain arrangement of walls hereinafter more fully described.

In the accompanying drawings:—

Figure 1 is a vertical sectional view of a 35 casting carried by the lower end of the cylinder in which the plastic material is compressed by forcing it through the casting.

Figure 2 is a horizontal sectional view taken on the line 2—2 of Figure 1 showing 40 the casting.

Figure 3 is a similar view of a slightly modified form of casting.

Figure 4 is a view similar to Figures 2 and 3 showing a still further modified form 45 of casting.

Referring now to the drawings 1 represents the cylinder in which is arranged the plunger 2 for compressing the refractory material in the cylinder and forcing it 50 through a casting as will be hereinafter more fully described. The refractory material is fed into the cylinder below the plunger in any desired manner and the lower end of the cylinder has attached thereto a sec-

tion 3 carrying a spreader 4 which is adapted to spread the refractory material before it passes to the casting. Carried by the lower end of the section 3 is a section 5 which has at its lower end, an annular outwardly extending flange 6 to which is bolted 60 the outer section 7 of the casting by means of the bolts 8. This casting section has its inner periphery provided with four inwardly bellied walls 9, 10, 11 and 12 which are connected at each corner by three outwardly curved walls 13, 14 and 15 which are arranged on a smaller arc of a circle than the inwardly bellied walls. The upper ends of all of these walls are slightly beveled as indicated at 16 for the purpose hereinafter 70 more fully described.

The spreader 4 has a downwardly extending cylindrical member 17 having an internally screw-threaded opening 18 and fitting against the lower end of the said cylindrical member is a second member 19 of the casting which has four inwardly bellied walls 20, 21, 22 and 23 which are arranged in the same arc of a circle as that of the walls 9, 10, 11 and 12. These inwardly bellied walls 20, 21, 22 and 23 of the casting member 19 are connected at the corners by the straight walls 24, 25, 26 and 27. The upper edges of these walls, carried by the casting section 19 are beveled as indicated 85 at 28 whereby the passage 29 between the casting members 7 and 19 has a flared upper end to receive the plastic refractory material and compress the same during its passage between said casting members.

In the modification shown in Figure 3 the casting member 7 is arranged with walls exactly like that shown in Figure 2 of the drawings and like reference numerals indicate like parts. The casting member 19, however has four straight walls 30, 31, 32 and 33 connected by the straight walls 34, 35, 36 and 37.

In the modification shown in Figure 4, the casting member 7 is provided with the four inwardly bellied walls 38, 39, 40 and 41 and each provided with the outwardly curved wall 46 intermediate their ends and forming the supporting ribs as will be readily seen by reference to the application herebefore mentioned. The inwardly bellied walls 38, 39, 40 and 41 are connected by the straight walls 42, 43, 44 and 45. In this

form shown in Figure 4 the inner member 47 of the casting has four straight walls 48, 49, 50 and 51 connected at the corners by short curved walls 52.

5 Having thus fully described our invention what we claim is:—

1. A casting for feeders for ingot molds, comprising an outer member having inwardly bellied walls oppositely arranged 10 and an inner member having correspondingly arranged outer walls.

2. A casting for feeders for ingot molds, comprising an outer member having inwardly bellied, oppositely arranged walls 15 and an inner member having outer walls approximately of the same shape.

3. A casting for feeders for ingot molds comprising an outer member having inwardly bellied walls oppositely arranged 20 and connected by oppositely arranged curved walls, curved in the opposite direction and an inner member having outer walls of ap-

proximately the same shape as the inner walls of the outer member.

4. A casting for feeders for ingot molds 25 comprising an outer member having four inwardly bellied inner walls each wall connected by three curved walls curved in the opposite direction and the inner member having outer walls of approximately the 30 same shape as the inner walls of the outer member.

5. A casting for feeders for ingot molds comprising a member having four inwardly bellied walls connected by outwardly curved 35 walls arranged in a different arc of a circle and an inner member having straight walls connected at the corners by short curved walls.

In testimony whereof we affix our signatures.

BLOOMFIELD H. HOWARD.
ERNEST J. TURNER.
